UNITED STATES PATENT OFFICE

2,490,601:

DEALKYLATION OF ALKOXYARYLS

Bernard W. Rottschaefer, East Greenbush, N. Y., assignor to General Aniline & Film Corporation, New York, N. Y., a corporation of Delaware.

No Drawing. Application July 3, 1946; Serial No. 681,412.

6 Claims. (Cl. 260—571.)

1

The present invention relates to a method of dealkylating alkoxyaryls and is particularly concerned with an improved method in which an alkoxyaryl compound (especially an alkoxy aryl-amino compound) is dealkylated by treatment with a Friedel-Crafts reagent in a saturated aliphatic or alicyclic hydrocarbon solvent free from unsaturates and aromatics.

The use of a Friedel-Crafts reagent as a dealkylating agent for the dealkylation of alkoxyaryls has heretofore been suggested. However, such prior art processes have generally been accompanied by the formation of tars and gums. I have now found that if the aromatic solvents (such as benzene, toluene and the like) which have heretofore been employed, are replaced by a saturated aliphatic or alicyclic hydrocarbon medium free from unsaturates and aromatics, the dealkylation of alkoxyaryl compounds using a Friedel-Crafts reagent is readily carried out with a good yield of the desired product in a high degree of purity and free of tars and other undesirable by-products. I have also found that somewhat smaller amounts of Friedel-Crafts reagent can be employed and in the case of alkoxyaryl amines, the reaction can be carried out employing the free base instead of the salt of the base.

The process of the present invention is applicable to the dealkylation of compounds represented by the following general formula:

R—O—Alkyl.

in which R represents an aromatic hydrocarbon ring which may be either mono-cyclic or polycyclic and which may contain such nuclear substituents as alkyl, aryl, halogen, hydroxy, alkoxy, nitro, amino and the like, but which is preferably free of aryloxy substituents. As examples of such compounds may be mentioned anisol, anisidine, phenetole, phenetidine, guaiacol, dianisidine and the like.

In practicing the process of this invention, the alkoxyaryl compound to be dealkylated is dissolved or suspended in a saturated aliphatic or alicyclic hydrocarbon solvent free from unsaturates and aromatics. Any saturated hydrocarbon which is liquid at the reaction conditions may be employed as the solvent for the reaction. As examples of suitable solvents may be mentioned methylcyclohexane, heptane, octane, nonane and various petroleum fractions free of unsaturates and aromatics. A suitable solvent can readily be prepared by treating a gasoline or similar liquid petroleum fraction with approximately an equal volume of sulfuric acid in order to remove any

unsaturates or aromatics which it may contain. In order to avoid the use of pressure, it is desirable that the solvent employed have an initial boiling point of at least 90° C. At the same time, too high a boiling solvent is preferably avoided in order that the solvent may readily be recovered by distillation. I therefore preferably employ as solvent a saturated hydrocarbon boiling within the range of approximately 90—150° C. The relative amount of solvent employed during the reaction is not highly critical so long as a sufficient amount is used that the reaction mixture is readily fluid.

In order to effect the dealkylation of the alkoxyaryl compound dissolved or suspended in the saturated hydrocarbon solvent, a Friedel-Crafts reagent is added to the mixture of alkoxyaryl compound and solvent, preferably at a temperature below about 50° C. and the reaction mixture is then heated to a temperature at which the desired dealkylation reaction proceeds at a satisfactory rate, but below that at which undesired secondary reactions take place. A temperature of at least approximately 90° C. is preferred in order to obtain a satisfactory rate of reaction, while temperatures much above 150° C. are preferably avoided in order to prevent undesirable side reactions. If the solvent employed for the reaction refluxes within a range of about 90° C. to 150° C., the reaction may advantageously be carried out at atmospheric pressure and at the reflux temperature of the solvent. However, superatmospheric pressure may be employed if necessary in order to maintain the material in liquid phase.

As a Friedel-Crafts reagent I preferably employ aluminum chloride or bromide. The relative amount of Friedel-Crafts reagent employed will vary with the specific reagent used. In general, the approximate amount of one mol aluminum chloride is employed per an equivalent of alkoxy, except where an active group such as an amine group is present, in which case an additional equivalent quantity of Friedel-Crafts reagent is used. For example, when dealkylating phenetole, only one mol aluminum chloride need be used. However, in the case of dianisidine, four mols of aluminum chloride are used, two for consumption in dealkylating the two methoxy groups present, and two for reaction with the two amine groups present.

The following examples describe in detail specific preferred embodiments of the present invention.

Example I

A gasoline fraction which refluxed at approxi-

mately 100°-110° C. was refluxed for several hours with an equal volume of 100% H₂SO₄ in order to remove any unsaturated or aromatic hydrocarbons which it might have contained, and was then separated from the H₂SO₄ layer. To 2,000 cc. of the saturated hydrocarbon thus obtained there were added 244 grams (1 mol) of dry dianisidine and 580 grams (4.36 mols) of anhydrous aluminum chloride were then added at a temperature of approximately 50° C. The material was then gradually heated to reflux (100°-110° C.) and was refluxed for approximately 6 hours to complete the reaction. The charge was then poured into 7,000 cc. of water containing 4 mols of hydrochloric acid. The solvent was removed by steam distillation and the charge diluted to approximately 8 liters. The product—3,3'-dihydroxy benzidine—was completely dissolved in the acid mother liquor and any traces of impurities were removed by treating with charcoal and filtering.

The 3,3'-dihydroxy benzidine was then recovered from the acid mother liquor in the form of its sparingly soluble sulfate by adding about 800 grams of Na₂SO₄ to the mother liquor and cooling to room temperature. By this procedure a very pure grade of 3,3'-dihydroxy benzidine was obtained in excellent yield.

Example II

142.5 grams of 5-chloro-o-anisidine were added to 2,000 cc. of gasoline fraction treated as described in Example I. There were then added 267 grams (2 mols) of anhydrous aluminum chloride at a temperature of approximately 45° C. The charge was then gradually raised to reflux (125° C.) and refluxed for 6 hours to complete the reaction. The charge was then drowned into water containing an excess of hydrochloric acid and the gasoline removed by steam distillation. The product—4-chloro-o-aminophenol—was recovered in excellent yield by crystallization from the acid mother liquor.

Example III

244 grams (1 mol) of dry dianisidine and 533 grams (4 mols) of anhydrous aluminum chloride were added to 2,000 cc. of methylcyclohexane at a temperature of approximately 50° C. The material was then gradually heated to reflux and was refluxed for approximately 6 hours to complete the reaction. The charge was then poured into 7,000 cc. of water containing 4 mols of hydrochloric acid. The solvent was removed by steam distillation and the charge diluted to approximately 8 liters. The product—3,3'-dihydroxy benzidine—was purified as in Example I.

It will be understood that the foregoing examples are illustrative only of preferred embodiments of the present invention and various modifications within the limits heretofore specified may be made therein without departing from the teachings of this invention.

I claim:

1. The process of dealkylating alkoxy aryl-amino compounds free of aryloxy groups, which comprises heating to a temperature of 90-150° C. in a distillable saturated hydrocarbon liquid a mixture of said alkoxy aryl-amino compound and an aluminum halide Friedel-Crafts agent in such molar proportions that one mol of said Friedel-Crafts agent is present for each alkoxy and amino group in said alkoxy aryl-amino compound.

15 2. The process of dealkylating alkoxy aryl-amino compounds free of aryloxy groups, which comprises heating to a temperature of 90-150° C., in a saturated hydrocarbon liquid boiling within the range of about 90-150° C., a mixture of said alkoxy aryl-amino compound and an aluminum halide Friedel-Crafts agent in such smaller proportions that 1 mol of said Friedel-Crafts agent is present for each alkoxy aryl-amino group in said alkoxy aryl-amino compound.

20 3. The process as defined in claim 2 wherein the aluminum halide specified is aluminum chloride.

25 4. The process of dealkylating anisidine, which comprises refluxing in a saturated hydrocarbon liquid boiling at from 90-150° C. a mixture of anisidine and an aluminum halide Friedel-Crafts agent in a molar ratio of 1:2.

30 5. The process of producing 3,3'-dihydroxy benzidine by dealkylating dianisidine, which comprises refluxing in a saturated hydrocarbon liquid boiling at from 90-150° C. a mixture of dianisidine and an aluminum halide Friedel-Crafts agent in a molar ratio of 1:4.

35 6. The process of producing 4-chloro-o-aminophenol by dealkylating 5-chloro-o-anisidine, which comprises refluxing in a saturated hydrocarbon liquid boiling at from 90-150° C. a mixture of 5-chloro-o-anisidine and an aluminum halide Friedel-Crafts agent in a molar ratio of 1:2.
